OXYACETYLENE WELDING OR CUTTING EQUIPMENT

Henry Alfred Ernest Talley, London, England, assignor to Medical & Industrial Equipment Limited, London, England

Application November 27, 1943, Serial No. 512,072
In Great Britain March 4, 1943

5 Claims. (Cl. 158—27.4.)

1

This invention relates to oxy-acetylene welding and cutting apparatus its object being to provide a novel construction of apparatus which will ensure economy and provide greater efficiency with unskilled operators, such construction consisting mainly in controlling the supply of one of the gases by a sensitive demand regulator, the diaphragm of which is actuated under the influence of the suction caused by the flow of the gases through a jet and restricted tube towards the burner jet.

A further feature of the invention consists in the association with the oxygen and acetylene gas supplies of fine adjustment control means by which further regulation of the supply of the gases can be calibrated to provide automatic action.

It is thus possible to obtain a constant and correct flame at the burner jet by controlling the gas pressures and providing suitable jet orifices for the oxygen and the final burner nozzle.

So that the invention may be fully understood and readily carried into effect I will now describe the same, reference being had to the accompanying drawing which shows by way of simple dia-grammatic illustration two forms of construction wherein:

Figure 1 is a part vertical elevation of the apparatus using fine adjustment controls on both the oxygen and the acetylene gas supplies; Fig. 2 is a part vertical section of a simplified construction of more practical nature which dispenses with the fine adjustment valves. Fig. 3 is an enlarged detail sectional view illustrating the manner of mounting the diaphragm-actuated levers.

In the construction shown at Fig. 1 acetylene gas from the usual cylinder or other source of supply A passes to a fine adjustment control device B which is shown, described, and claimed in my co-pending application filed March 31, 1944, Serial No. 528,828; and which has now become Patent No. 2,384,354, granted September 4, 1945, (any usual regulator cock such as 1 being included if desired) thence to the restricted tube C and to the burner nozzle at D. The oxygen supply from a cylinder E or other supply passes to a sensitive demand regulator F (an ordinary regulator 1* being interposed if desired), thence to a second fine adjustment control device B and to the oxygen jet C* within the restricted tube C where it admixes with the acetylene gas and passes to the burner nozzle D. Negative pressure occurs at the point where the oxygen jet meets the restricted tube.

The sensitive demand regulator F is of the kind

2

described in my co-pending application Serial No. 528,829, filed March 31, 1944, and consists of a casing in which is secured a resilient or flexible diaphragm 14, the casing having an extension 15 to which the oxygen supply is connected at 16, the end of such extension being closed, if desired, by a plug 17. A valve seat 18 is located in the extension and adapted to be normally closed by a valve 19 whose stem or spindle 20 is pressed by a headed pin or flanged neck 21 attached to the junction point 22a of two or more levers 22 fulcrumed intermediate their ends in the casing of the diaphragm 14 and engaged by their free ends with the diaphragm itself. The levers 22 which are disposed radially with relation to the casing 24a have inner and outer arms, the inner arms being connected with the headed pin 21 and the outer arms being engaged by the diaphragm 14 so that when the diaphragm is moved inwardly by atmospheric pressure the headed pin will be drawn outwardly against the action of the spring 23 and will withdraw the valve 19 from its seat 18 and will permit oxygen from the cylinder E to pass through the extension 15 to the second fine adjustment control. The diaphragm is open to the atmosphere at 24.

Obviously the acetylene gas supply may be taken to the sensitive demand regulator F instead of the oxygen.

30 The fine adjustment valves are adjusted so that the amount of gas allowed to pass through the outlet 4 is predetermined and constant. The effect of the diaphragm is that by means of a negative pressure being applied to it, it opens a valve 35 to admit gas to the restricted tube.

In the construction shown at Fig. 2, which adjustment valves are dispensed with and the application filed March 31, 1944, Serial No. 528,829, the same principle is involved except that the fine adjustment valves are dispensed with and the apparatus generally given a more practical form.

The acetylene and oxygen from the usual sources of supply are connected respectively to the unions or sockets 25, 26 which connect with 45 passages housed or formed in a handle portion 27 terminating in a chamber G. The oxygen supply passes by a passage 28 shown dotted, in the periphery of such chamber directly to the jet 29 whilst the acetylene enters the chamber through 50 an inlet 30, then through a valve opening 31 provided in said chamber and out through the outlet 32 into a restricted tube 33 having a restricted area adapted to cooperate with the jet to produce sub-atmospheric pressure when the gas is discharged from the jet.

The valve opening 31 is normally closed by a valve 35 sealed from the atmosphere whose stem 36 rests in a recess 37 of a pin or neck 38 carried by a plate 39 to which are affixed the ends of two or more levers 40 fulcrumed at 41 to the casing of a sensitive demand regulator 44 embodying a diaphragm 43 on which the free ends 42 of the levers 40 bear. The casing has an opening at 45 so that the diaphragm 43 is subjected to atmospheric pressure on that side. Furthermore a passage 46 is provided between the diaphragm 43 and the outlet 32.

The pressures of the gases are suitably regulated as for example oxygen at 30 lbs. per square inch, and acetylene at 60 lbs. per square inch and the jets are similarly selected as for example 70 amal for the oxygen and 250 amal for the burner nozzle jet which means that the orifices are of a size respectively to allow gas to flow at the rate of 70 and 250 cc. per minute at a pressure equal to six inches of water; in this manner a constant and correct welding or cutting flame can be obtained without risk of explosion so that it is possible for unskilled labour to use the apparatus effectively.

The suction created by the flow of the oxygen causing a negative pressure at the mouth of jet 29 in Venturi tube 34 will force the diaphragm 43 to act on the levers 40 so bringing about the movement of pin 38 against the action of its spring 47 to open the valve 35 and permit the flow of acetylene to the Venturi tube 33.

I claim:

1. Oxy-acetylene cutting and welding apparatus comprising a welding tube including a jet and a tube surrounding the jet and having a restricted area adapted to cooperate with the jet to produce sub-atmospheric pressure, a supply of oxygen gas, a fine adjustment control therefor, a supply of acetylene gas, a sensitive demand regulator, a passage from the supply of acetylene gas to the sensitive demand regulator, said sensitive demand regulator including a diaphragm having one of its faces subjected to atmospheric pressure and positively actuated by the same when its other face is subjected to sub-atmospheric pressure, a valve sealed from the atmosphere and interposed in the acetylene gas passage and controlled by said diaphragm to open when the diaphragm is subjected to said sub-atmospheric pressure, the sensitive demand regulator being provided with an outlet, a second fine adjustment control connected to the outlet of said regulator, and passages extending from the fine adjustment controls to the jet and said tube.

2. Oxy-acetylene cutting and welding apparatus comprising a welding tube including a jet and a tube surrounding said jet and having a restricted area adapted to cooperate with the jet to produce sub-atmospheric pressure, a body forming a handle provided with sockets, a supply of oxygen gas connected with one of the sockets, a supply of acetylene gas connected with the other socket, a chamber provided on the handle and having a passage in its peripheral wall, a conduit between the socket for the oxygen supply and said peripheral passage and from the latter to said jet

for creating a sub-atmospheric pressure within the tube at the mouth of the jet, a conduit between the socket for the acetylene gas and an inlet to said chamber, a conduit from an outlet of said chamber to the tube, a valve sealed from the atmosphere and interposed between the inlet and outlet of said chamber for the acetylene gas, and diaphragm actuated means including a diaphragm having one of its faces subjected to atmospheric pressure and positively actuated by the same when its other face is subjected to sub-atmospheric pressure, whereby the valve will be actuated by the diaphragm and opened when the diaphragm is actuated by atmospheric pressure.

10 3. Oxy-acetylene cutting and welding apparatus as claimed in claim 2 having a diaphragm actuated means comprising a casing fast to one end of the chamber, a flexible diaphragm therein, levers fulcrumed intermediate of their ends to said casing and bearing at one end on the diaphragm, a spring pressed plate connected to the other end of said levers, and a headed pin on said plate adapted to move within the chamber and contact with the valve therein.

15 4. Oxy-acetylene cutting and welding apparatus comprising a jet, a tube surrounding said jet and having a restricted area adapted to cooperate with the jet to produce sub-atmospheric pressure, a supply of oxygen gas, a supply of acetylene gas, means for ensuring constant flow of said gases to the jet and the tube including conduits for said gases, the flow of gas through the jet creating a sub-atmospheric pressure within the tube at the mouth of the jet, and a diaphragm controlled 20 30 35 40 valve sealed from the atmosphere and interposed in one of the conduits and including a diaphragm having one of its faces subjected to atmospheric pressure and positively actuated by the same when its other face is subjected to sub-atmospheric pressure, and a valve operatively connected with said diaphragm and opened by the same when the diaphragm is actuated by atmospheric pressure.

5. Oxy-acetylene cutting and welding apparatus 45 comprising a welding tube including a jet and a tube surrounding the jet and having a restricted area adapted to cooperate with the jet to produce sub-atmospheric pressure, a source of oxygen gas, a source of acetylene gas, a conduit conveying oxygen gas to said jet for creating a sub-atmospheric pressure in the tube at the mouth of the jet, another conduit conveying acetylene gas to the tube, a diaphragm actuated regulator interposed in one of said conduits and including a diaphragm having one of its faces subjected to atmospheric pressure and positively actuated by the same when its other face is subjected to a sub-atmospheric pressure so that the flow of gas takes place only when sub-atmospheric pressure is set up at the mouth of the restricted arc of the welding tube when gas flows through said jet, and a valve sealed from the atmosphere and interposed in the other conduit and controlled by the diaphragm for opening the valve when the diaphragm is subjected to said sub-atmospheric pressure.

HENRY ALFRED ERNEST TALLEY.
